Primary Examiner — Mark Goodwin(74) *Attorney, Agent, or Firm* — Colin P. Cahoon; Celina M. Orr; Carstens & Cahoon, LLP(57) **CLAIM**

The ornamental design for a packaging container, as shown and described.

DESCRIPTION

FIG. 1 is a perspective view of a packaging container showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The features shown in broken lines in the drawings depict environmental subject matter only and form no part of the claimed design.

UNITED STATES PATENT AND TRADEMARK OFFICE
CERTIFICATE OF CORRECTION

PATENT NO. : D658,077 S
APPLICATION NO. : 29/400394
DATED : April 24, 2012
INVENTOR(S) : Stephen D. Newman

Page 1 of 1

It is certified that error appears in the above-identified patent and that said Letters Patent is hereby corrected as shown below:

On Title page 1, item (75); of the above-referenced design patent, the spelling of the inventor's name should be changed from Stephan with an "a" to Stephen with an "e" as follows:

Stephen D. Newman

Signed and Sealed this
Twenty-sixth Day of June, 2012

David J. Kappos
Director of the United States Patent and Trademark Office
